UNITED STATES PATENT OFFICE.

HOWARD L. WADSWORTH, OF CLEVELAND, OHIO.

SAND CUTTING AND SCREENING MACHINE.

Application filed November 17, 1919. Serial No. 338,655.

To all whom it may concern:

Be it known that I, HOWARD L. WADSWORTH, a citizen of the United States, and a resident of Cleveland, county of Cuyahoga, and State of Ohio, have invented a new and useful Improvement in Sand Cutting and Screening Machines, of which the following is a specification; the principle of the invention being herein explained, and 10 the best mode in which I have contemplated applying that principle so as to distinguish it from other inventions.

The present improvements, relating, as indicated to sand-cutting and screening machines, are directed to a machine for use in large foundries where crane service is available, and where the machine may be lifted bodily by a crane and "spotted" before a pile or windrow of sand which is to be cut. 20 To the accomplishment of the foregoing and related ends, said invention, then, consists of the means hereinafter fully described and particularly pointed out in the claims.

The annexed drawing and the following 25 description set forth in detail certain mechanism embodying the invention, such disclosed means constituting, however, but one of various mechanical forms in which the principle of the invention may be used.

30 In said annexed drawing:—

Fig. 1 is a side elevation of my improved machine; Fig. 2 is a plan view thereof; and Fig. 3 is a diagrammatic view on a reduced scale showing the machine when in operation by means of a crane.

In Fig. 1 there is shown a framework consisting of spaced parallel side members 1, uprights 2 and transverse members 3, the entire framework being mounted upon two 40 pairs of supporting wheels 4 and 5. Mounted at the forward end of the machine are two parallel vertical shafts 6 and 7, upon which are carried spiders 8 provided with sand-cutting blades or plates 9. These two cutting cylinders are duplicates and the cutting blades are so arranged that they overlap one another, but are never in contact, as the position of the cutting blades is staggered. These sand-cutting cylinders are 45 operated in the direction shown by the arrows in Fig. 2 by means of bevel gears 10 11, 12 and 13, of which the bevel gears 11 and 12 are mounted on the horizontally disposed shaft 14, which is driven through

55 gears 15 and 16, the latter being rotated by means of an electric motor 17, which is carried on the frame of the machine.

The machine is provided with no means for propelling it over the ground, but has an ordinary crane bale 19, by which the entire 60 machine may be lifted by the cable 20 from a crane cab and carried to the place where it is to be operated. The frame of the machine also provides, at the forward end, a means for attachment to a tow line 21, and 65 in Fig. 3 the machine is shown when being towed by a crane. In this figure there is shown a movable crane 22 operable along spaced rails or guides 23 by the usual means. There is usually of course a crane cab which 70 is operable transversely of the rails 23, but this is not indicated in the figure. The machine is first spotted in front of a pile of sand, which may be either in the form of a windrow 24, as shown in Fig. 3, or a large 75 heap, and is then towed over the pile of sand at the same time that the cutting cylinders are operated. These cylinders operate to cut into the sand and take successive slices 80 from the vertical face of the pile, passing the sand between the two cylinders, and then out at the rear of the machine between the side plates 25, which are shown in Figures 1 and 2. These plates limit the throw of 85 the sand by the cylinders and leave a regular pile of sand after it has been cut. If the machine is being operated to cut a large heap of sand it may first be spotted before one side of the pile, and then towed across this side to cut it, after which it is returned 90 to its original position and used to cut successive portions of the single heap.

Other modes of applying the principle of my invention may be employed instead of the one explained, change being made as 95 regards the mechanism herein disclosed, provided the means stated by any of the following claims or the equivalent of such stated means be employed.

I therefore particularly point out and distinctly claim as my invention:—

1. In a machine of the character described the combination of a rectangular vehicle frame and supporting wheels therefor, sand cutting means mounted on said frame with in the same, a crane bail attached to said frame for hoisting the same, and a towing line attached at one end of said frame where-

by the same may be towed down over the ground by an overhead moving element.

2. In a machine of the character described the combination of a rectangular vehicle frame and supporting wheels therefor, a crane bail attached to said frame for hoisting the same, a towing line attached at one end of said frame whereby the same may be drawn over the ground by an overhead moving element, sand cutting means mounted on said frame within the same, and independent motive means for driving the same.

3. In a machine of the character described, the combination of a vehicle frame and supporting wheels therefor, and vertically arranged overlapping sand cutting means mounted on said frame within the same and extending the entire width of said frame.

4. In a machine of the character described, the combination of a vehicle frame and supporting wheels therefor, and sand cutting means comprising two rotatable cylinders vertically mounted adjacent to and within one end of said frame and adapted to overlap

one another, said cylinders extending laterally the entire width of said frame.

5. In a machine of the character described, the combination of a vehicle frame and supporting wheels therefor, sand cutting means comprising two rotatable cylinders vertically mounted adjacent to and within one end of said frame, said cylinders extending laterally the entire width of said frame, and lateral guide means adapted to feed sand toward said cylinders.

6. In a machine of the character described, the combination of a vehicle frame and supporting wheels therefor, and sand cutting means mounted on said frame within the same and extending the entire width of said frame, said sand cutting means comprising two cooperating vertically mounted bladed cylinders, said cylinders being mounted on parallel axes with their blades arranged to overlap each other.

Signed by me, this 5th day of November, 1919.

HOWARD L. WADSWORTH.
